UNITED STATES PATENT OFFICE.

FRANK H. DUNBAR, OF CLEVELAND, OHIO.

ASH GATE.

Application filed March 5, 1923. Serial No. 622,728.

To all whom it may concern:

Be it known that I, FRANK H. DUNBAR, a citizen of the United States, residing at Cleveland, in the county of Cuyahoga and State of Ohio, have invented a certain new and useful Improvement in Ash Gates, of which the following is a full, clear, and exact description, reference being had to the accompanying drawings.

10 This invention relates to closures for hoppers and is particularly adapted to hoppers for receiving ashes or other loose material.

In the usual practice ash hoppers are designed to hold the hot ashes until they can 15 be discharged in suitable transporting devices by opening the door of a gate construction beneath the discharge opening. In order to quench the hot ashes to prevent them from injuring the walls of the hopper and 20 stoker parts considerable water is sprayed on them. It is desirable therefore to remove this water in a satisfactory and efficient manner.

An object of my invention is to provide a 25 door for such hoppers which will at all times receive and discharge easily and quickly all such liquid without allowing it to escape and fall in undesirable places.

A further object of the invention is to provide a simple and efficient means for keeping the passages for conducting the water 30 from becoming obstructed by settling of the fine sediment and material carried along with the water.

35 Another object of the invention is to provide the closure mechanism with liquid conducting passages so arranged that the material carried along with the water cannot settle in certain passages and mechanism is 40 provided for positively removing the material from the other passages.

These and other objects will be apparent from the following description and attached drawings forming a part of this application.

45 In the accompanying drawings forming a part of this application,

Figure 1 is a section on line 1—1, Fig. 2, showing the door in plan.

Fig. 2 is a vertical section taken on line 50 2—2, Fig. 1.

Fig. 3 is an elevation showing the tracks in section as indicated by line 3—3, Fig. 1.

Fig. 4 is a vertical section of the bottom of the hopper and door on line 4—4, Fig. 1.

Fig. 5 is a fragmentary sectional view 55 similar to Fig. 4 except that the door is in open position.

The lower portion of the hopper or bin for holding the material is indicated at 1, and consists of the usual metal walls 2 lined with fire brick or other refractory material 60 3. Surrounding the discharge opening of the hopper is a gate construction comprising a frame and a door, the frame 4 comprising sides 4' and ends 4". The frame is supported from the hopper by any suitable means such as angle iron 5 to which the frame is bolted.

The sides 4' of the frame are preferably 65 of channel construction, each having a vertical web 6 and flanges 7 and 8 projecting outwardly, the lower flanges 7 forming tracks on which the door is suspended for movement as described hereinafter. The sides 4' are provided also on the inside with 70 flanges 9 on which the lower edges of the refractory material rests. The door 10 is carried by arms 11 to which are attached rollers 12 to run on the flanges 7 of the frame. The door is reciprocated to open and closed 75 position by any suitable mechanism such as a door operating piston and cylinder, the piston rod being shown at 10'. Adjacent the ends of the frame sides 4', suitable track extensions 13 are secured upon which the 80 door is carried during opening and closing movements.

Along the sides and preferably one end 85 of the door are suitable channels or troughs 14 and 15 for carrying off the liquid which 90 comes through the material in the hopper. These may be attached to or made integral with the door. The side troughs 14, 15 are substantially horizontal and underlie the flange 9 of the frame, there being sufficient 95 clearance provided, however, between the inner flange of the trough and the extremity of the flange 9 to permit the water to escape outwardly easily but preventing any large material from passing through. In order to 100 direct the water into the trough and prevent its being forced entirely over the edge of the door, a suitable rib may extend downwardly from the flange 9 or the outer flange 16 of the trough may be made higher than the 105 space between the inner flange of the trough and the opposing flange 9 of the frame.

The front end of the door is preferably

provided with a trough 17, the bottom of which is relatively sharply inclined so that the fine sediment and material which is carried along with the water cannot deposit in the trough as when the slope is relatively gradual. The trough of course would cease to function if it became full of sediment, and the water at the front of the door would simply escape over the edge. The trough 17 5 may slope continuously from one side to the other but preferably is designed to slope to both side troughs from a midpoint. This construction gives the same fall as the single slope and in half the width of the door so 10 it is much more effective in causing the water to run quickly to the side troughs, thus preventing the trough 17 from filling up. The trough is also curved to direct the liquid into the side troughs 14, 15 at an angle less than 15 a right angle.

The side troughs 14, 15 preferably are substantially horizontal as I do not depend upon the flow of liquid to keep them clean. I provide a positive means to remove their 20 contents every time the door is moved. This means consists of plows or scrapers 20 carried by the frame or integral therewith which conform to the cross sectional shape of the troughs. The scrapers are designed 25 to have sufficient clearance so that they will not interfere with the movement of the door when opening or closing and yet will remove substantially all the contents of the troughs when the door is moved to fully open position. The front ends of the troughs 14 and 30 15 are formed with inclined portions 21 extending forwardly and upwardly to prevent leakage of water over the ends of the trough. They permit, however, any material which 35 has collected in front of the scraper 20 when 40 the door is closing to pass out over the inclined end, thus preventing packing of the material against the ends 21 and permitting the door to be moved to fully closed position.

At the rear of the door and secured to the frame 4 is a fixed trough 25 which underlies the rear end of the door and receives the water from the side troughs 14, 15 and 50 the rear end of the door, all of these being curved and lipped to deliver the water into the trough and prevent it from running back under the gate. The trough 25 has suitable discharge pipes 26 for conducting the liquid 55 and sediment where desired.

A suitable nozzle (diagrammatically indicated at 22) may be provided for throwing streams of water in both directions to positively clean the trough 17 when desired. 60 While the gate construction has been shown herein as applied to an inwardly sloping hopper and one having metal walls lined with fire brick, it is to be understood that the gate mechanism is applicable to any 65 of the types of ash hoppers in use simply

by adapting the frame and the door to the particular design of hopper.

It will also be seen that by providing a positive means for cleaning the side troughs at each movement of the door I am enabled 70 to use a substantially horizontal side trough and to give the end or front trough on the door a slope corresponding to the entire depth of the door which is not possible where the sloping side troughs are used, thus enabling me to obtain a relatively steeper slope 75 to the front trough or troughs.

Furthermore, it is to be understood that the particular forms of apparatus shown and described, and the particular procedure set 80 forth, are presented for purposes of explanation and illustration and that various modifications of said apparatus and procedure can be made without departing from my invention as defined in the appended claims. 85

What I claim is:

1. The combination in a closure mechanism for bottom discharge hoppers, of a frame and a door reciprocable thereon, said door having drain troughs along its sides 90 and means for scraping material from said side troughs upon relative movement of said door and said means.

2. The combination in a closure mechanism for bottom discharge hoppers, of a frame, a door reciprocable thereon, said door having troughs along its sides, means to prevent material from falling into said troughs from the hopper and means to clean 95 said troughs upon relative movement of the 100 cleaning means and the door.

3. The combination with a hopper provided with a bottom discharge opening, of a frame surrounding said opening and provided with outturned flanges, a door having 105 suspending means to reciprocate on said flanges to open and close said opening, said door having liquid carrying troughs along its sides, and means for removing material from said troughs upon relative movement 110 of said door and said removing means.

4. A closure mechanism for bottom discharge hoppers comprising a frame, a door reciprocable thereon, said door having drain 115 troughs along its sides, and means carried by the frame for scraping material from said side troughs when the door is moved.

5. A closure mechanism for bottom discharge hoppers comprising a frame, a door reciprocable thereon, said door having drain 120 troughs along its sides, and scrapers conforming to the cross-sectional shape of the troughs and projecting into said side troughs to prevent material in the trough from passing the scraper when the door is being 125 opened.

6. A closure mechanism for a hopper having a bottom discharge opening comprising a frame having inwardly disposed flanges, a door reciprocable on the frame and hav- 130

ing drain troughs along its sides and disposed beneath said flanges, means carried by the frame to scrape said side troughs when the door is being operated, and means to prevent material from packing behind the scraper thus permitting the door to close.

7. A closure mechanism for a hopper having a bottom discharge opening comprising a frame having inwardly disposed flanges, a door reciprocable on the frame and having drain troughs along its sides and disposed beneath said flanges, and means carried by the frame to scrape said side troughs when the door is being moved, said side troughs being open at their forward ends and having the bottoms upwardly and outwardly inclined.

8. The combination with a hopper provided with a bottom discharge opening, of a frame surrounding said opening, a door disposed between portions of said frame and adapted to reciprocate thereon to close said opening, the front and sides of said door having drain troughs, the bottom of the front trough having a relatively steep inclination and discharging into the side troughs, and means for removing material from said side troughs upon opening the door.

9. A closure mechanism for bottom discharge hoppers comprising a frame having webs and inner flanges, a door reciprocable on the frame, said door having communicating troughs on its front end and sides, said troughs being disposed beneath said flanges and relatively close to the webs of said frame, means carried by the frame for receiving the liquid and material from said door, and means for scraping material

from said side troughs upon relative movement of said door and said scraping means.

10. A gate construction for a hopper having a bottom discharge opening, comprising a frame having at its sides a vertical web and a flange disposed on each side thereof, a door reciprocable to open and close said opening, said door having troughs along the front and sides, the front trough having its bottom relatively steeply inclined, and means to clean the side troughs when the door is opening.

11. The combination with a hopper provided with a bottom discharge opening, of a frame surrounding said opening, a door disposed to reciprocate on the frame to open and close said opening, said door having a trough disposed approximately horizontally along one side thereof, means for scraping material from said side trough upon movement of the door, and a fixed trough adapted to receive liquid discharged from the door and said trough when the door is in closed position with respect to said opening.

12. The combination with a hopper provided with a bottom discharge opening, of a frame surrounding said opening, a door suspended therefrom and reciprocable thereon to open and close the discharge opening, said door having drain troughs at the front and sides thereof, said front trough having its bottom sloping relatively steeply toward each side of the door to discharge into said side troughs, said side troughs being substantially horizontally disposed, and means for removing material from said troughs.

In testimony whereof, I hereunto affix my signature.

FRANK H. DUNBAR.
